COLLAR HOLDER

Albert Joseph Rowan, Pawtuxet, R. I., assignor
to Taunton Pearl Works, a corporation of
Massachusetts

Application March 15, 1945, Serial No. 582,860

1 Claim. (Cl. 24—81)

1

This invention relates to a collar holder of the type formed with oppositely directed pairs of jaws to engage and grip the fabric of a collar on either side of the opening left for the necktie.

Difficulty is often encountered in the use of a collar holder in that the jaws slip along the fabric and become disconnected therefrom. Various means of a complicated structure have been devised for securely causing the jaws to grip the fabric.

One of the objects of this invention is to provide a simple and easily constructed arrangement for causing additional gripping pressure to be applied upon the fabric of the collar should movement occur of the jaw along the collar in a direction to detach the same.

Another object of this invention is to provide an arrangement whereby the edge of the collar may be easily inserted into the gripping jaws after start has been made while an initial additional resistance is provided to the withdrawal of the fabric from between the jaws.

Another object of this invention is to provide an arrangement whereby initial change in direction of movement of the fabric relative to the jaws will cause increasing pressure to be applied upon the fabric to resist such sliding movement between the jaws.

Another object of this invention is to provide a gripping device which will cause a gripping action on the back of the fabric of the collar rather than on the front surface thereof.

With these and other objects in view, the invention consists of certain novel features of construction, as will be more fully described and particularly pointed out in the appended claim.

In the accompanying drawings:

Fig. 1 is a top plan view of the collar holder;

Fig. 2 is a sectional view through the center binding portion of the holder and showing in section the fabric to be gripped;

Fig. 3 is a perspective view of the end portion of the rear jaw of one of the jaw pairs prior to the mounting of the movable member therein;

Fig. 4 is a view similar to Fig. 3 in which the movable member is mounted in position;

Fig. 5 is a sectional view through the mounting for the movable member;

Fig. 6 is a top plan view of the structure shown in Fig. 3.

Fig. 7 is a sectional view of the fabric showing several different positions of the movable member thereon.

In proceeding with this invention I provide an eye in the rear jaw of the collar holder and in

2

this eye mount a flattened loop formed of a bent-up piece of wire so that this loop may be rocked in this eye until it engages the stock of the jaw at one side of the eye. The arrangement is such that movement from one position to the other will cause a flexing of the jaws apart and greater pressure on the fabric between them.

With reference to the drawing, I have provided a bar 10 which forms the front jaws of the two pairs of jaws and a rear bar 11 which forms the rear jaws of both pairs of jaws. These jaws are bound together by a suitable clamp 12 so as to hold them in fixed relation. The jaws are both sufficiently flexible so that they may be moved toward and from each other.

The under surface or inside surface of the jaw 10 is substantially smooth. The sheet stock of the jaw or bar 11 is slit as at 14 and 15 (see Fig. 6) and the stock between the slits is raised as 20 at 16 (see Fig. 3) while the portions on either side of the slit are depressed as at 17 (see also Fig. 3). This forms an opening 18 beneath this raised stock 16 and the depression 17. A loop member 19 formed of a piece of wire which is round in cross section is bent substantially into the shape shown in Fig. 5 with its ends 20 extending into the opening 18 which causes the same to be pivotally mounted for rocking from a position so that its portion 21 engages the stock 30 at one side or the other side of the eye 18.

When fabric 22 (see Fig. 7) is moved inwardly between the jaws A and B the member 19 is rocked from its position 25 inwardly to its inner position 26 and easy access after such rocking is afforded. If, however, the fabric is attempted to be moved out from between the jaws A, B, then this member 19 will rock from a position 26 to a position 27 spreading the jaws, as shown in Fig. 7, by reason of its location in a plane at right angles to the general plane of the jaw B and thereby cause a maximum pressure to be exerted by it on the fabric forcing the fabric toward the jaw A. In this position there will be maximum resistance to the withdrawal of the fabric between the jaws. Further the doubled edge of the fabric, as shown in Fig. 2, will engage the member 19 and cause further resistance to movement of the fabric from between the jaws.

I claim:

50 A collar holder comprising oppositely directed pairs of jaws for gripping the spaced edges of a collar, one of said jaws of each pair having spaced slits extending longitudinally of the jaw with a portion of the stock between the slits deflected 55 from the surrounding portion of the jaw pro-

viding a pivotal bearing to provide opposed bearings between the portions on the outside of the slits and the portion between the slits, a member in the form of a loop passing through said bearing and extending about a portion of the stock between said slits to pivotally mount the loop member to rock through an arc on either side of a direction which is the shortest distance from said bearing to the other jaw for movement by the collar upon reversal of the relative movement 10 of the collar and jaws.
